EMIL CARL ZIMMERMAN, OF NEW YORK, N. Y., ASSIGNOR TO Q & C COMPANY, OF NEW YORK, N. Y., A CORPORATION OF MAINE.

GUARD-RAIL CLAMP.

1,418,120.

Specification of Letters Patent. Patented May 30, 1922.

Application filed March 24, 1920. Serial No. 368,210.

To all whom it may concern:

Be it known that I, EMIL CARL ZIMMERMAN, a citizen of the United States, residing at New York city, in the county of New York and State of New York, have invented new and useful Improvements in Guard-Rail Clamps, of which the following is a specification.

This invention relates to improvements in guard rail clamps and consists of a novel arrangement and construction of the parts adapted to possess important advantages over the types of clamps as heretofore used. My improved clamp is of an improved design which eliminates the necessity of employing the usual spacer blocks interposed between the rails and in consequence effects a desirable reduction in the number of parts and simplifies the installation thereof. The device of my invention is furthermore of very substantial construction adapting it for successfully resisting the thrusts and pounding of heavy traffic without danger of displacement from its effective position and moreover is of an improved design whereby the clamping yoke thereof will be retained in effective position independent of the securing means.

An important and valuable feature of my present invention resides in the provision of a shoulder or lug upon the upper or rail bearing surface of the yoke member positioned to be engaged by one of the rails, preferably the guard rail, and adapted to cooperate with the yoke and tightening wedge member in effecting the clamping of the rail in proper position and in the correlation therewith of a second tightening or spacing wedge arranged to engage the opposite end of the yoke and the other of the rails in a manner whereby the respective track rail and guard rail may be properly spaced to maintain the usual clearance of $1\frac{3}{4}$ " therebetween. My improved construction further permits of effecting adjustment of the clearance between the rails as desired and to compensate for wear on the rail heads. An additional important feature thereof consists in the arrangement and correlation of the several parts whereby when assembled they will be self-sustained in effective position with the yoke member thereof properly supported to resist the lateral strains irrespective of whether or not the clamp is fully tightened up, from which it

follows that not only is the effectiveness of the clamp maintained but the assembling of the device in operative position is materially simplified for it is not necessary to manually support the yoke member during the tightening operation. The described and other features and advantages of my present invention are shown in the accompanying drawing wherein like reference characters are applied to the corresponding parts of the several views.

In the drawing:—

Fig. 1 is a vertical sectional view illustrating my improved guard rail clamp as installed.

Fig. 2 is a plan view thereof showing the rails in horizontal cross section on line 1—1 of Fig. 2.

Fig. 3 is a partial view thereof showing a suitable modified form in elevation.

Fig. 4 is a detailed view of the shoulder member in side elevation and

Fig. 5 is a view similar to Fig. 3, illustrating a further modified construction.

In the preferred embodiment of my invention as illustrated in Figs. 1 and 2 the numeral 1 designates the guard rail to be secured or attached to the usual track rail 2 by means of the clamping yoke member 3.

An important feature of my present invention consists in the means employed for coacting with the yoke 3 to clamp the guard rail in position which, in accordance with my improved construction, is accomplished without attaching the yoke to either of the rails. The means provided therefor consists of suitable wedge members adapted to engage inner inclined surfaces 4 and 5 formed on the yoke 3 at the upwardly positioned inwardly turned end portions thereof. The wedge members or wedging shoes consist of a wedge member 6 provided at its outer side with an inclined wall or surface 7 adapted to engage the inclined surface 4 of the yoke with a wedging action. The wedge 6 as shown is interposed between the end of the yoke or surface 4 thereof and the track rail 2 so as to act as a spacing wedge therebetween. As will be noted adjustment or movement of the wedge member 6 longitudinally of the rail will vary the spacing or distance between the yoke end or surface 4 and the track rail and corresponding determine the position of the yoke in the plane at right angles to the longitudinal axis of 110

the rail. For the purpose of securing the wedge member 6 and retaining it in adjusted position the wedge member 6 is provided at its lower portion with an outwardly extending flange 8 formed integrally thereon and positioned to underlie the inwardly curved end portion of the yoke member 3. As best indicated in Fig. 2 the flange portion or ledge 8 is provided with a longitudinal series of apertures 9 therein adapted to receive a securing pin or bolt 21 arranged when positioned in said apertures to prevent longitudinal movement of the wedge member in the direction to withdraw it from clamping position.

A similarly formed spacing or tightening wedge member 10 is as shown interposed between the opposite end of the yoke and the guard rail 1 and is formed with a longitudinally extending inclined wall or wedging surface 11 positioned to engage the inner inclined surface 5 of the yoke end. The wedge member 10 has integrally formed thereon a ledge 8' arranged to underlie the end portion of the yoke and is provided with a longitudinal series of pin apertures 12 adapted to receive therein a locking pin 21 whereby it is secured in position against longitudinal displacement by the engagement of the pin 30 with the side of the yoke.

An important and valuable feature of the present invention consists in an improvement adapted to eliminate the necessity of employing the usual spacing blocks interposed between the respective rails for the purpose of determining the distance therebetween. For this purpose the guard rail is clamped in fixed relation to the yoke member 3 by clamping of the rail between shoulders 40 of the yoke by the action of the wedge member 10. In accordance therewith I have formed the yoke member 3 with an integral shoulder 15 upwardly projecting from the rail bearing surface of the yoke as shown and arranged between the respective rails. It is so arranged that the guard rail shall bear thereagainst and be clamped thereto by means of the wedging member 10, the latter having its inclined wall 11 engaging the inwardly directed coacting inclined surface 5 of the yoke member. As will be readily understood upon tightening up of the wedge member the yoke and guard rail will be rigidly clamped together. The lug 15 is of a form to be non-projecting over the rail flanges thereby to allow of the yoke being assembled with the tracks spiked in proper position on the ties.

With the guard rail and clamping yoke 3 attached or secured together in the manner described, the clamping thereof to the main track rail 2 is effected by inserting or driving in of the wedge member 6 between the track rail and clamp end as indicated and 65 the securing thereof by means of the secur-

ing pin 21. In the latter operation the relative spacing of the respective rails is determined by the positioning of the wedge member 6 so as to adjust the spacing as required. A possible adjustment is illustrated by the 70 dotted line 2^a of Figure 1. When so positioned the clamping yoke will be operative to withstand and oppose thrusts tending to separate the rails and as will be understood the usual spikes employed in securing the 75 rails will secure the rails in position and against movement toward one another. It will be noted that this construction readily permits of the wedge member 6 being tightened up or moved longitudinally to minutely 80 adjust the relative spacing of the rails and to compensate for wear thereon.

I have thus produced a guard rail clamping device having a reduced number of parts and which is particularly strong and 85 advantageous from a constructional standpoint.

As shown in Figs. 1 and 2 the parts may be formed so that in proper assembling, the wedge members 6 and 10 are driven into 90 tightening position from opposite directions and desirably in installation the wedge member 6 engaging the track rail may be driven in in the direction of normal traffic whereby the tendency thereof will be to 95 tighten up in use. Where the traffic is in the opposite direction the clamping yoke 3 may be formed whereby the wedge 6 may enter from the opposite side as indicated in the dot and dash lines of Fig. 2. As a further 100 constructional feature the wedge members 6 and 10 as here shown may be formed with projecting shoulders or lugs 16 to have point contact with the rails thereby permitting of a lighter construction.

While I have described and shown an approved embodiment of the several features of my invention it will be understood that various modifications may be made therein without departing from the scope thereof. 110 For instance, in Figs. 3 and 4 I have shown a suitable modification wherein the clamping shoulder on the upper rail bearing surface of the yoke member 3 is formed as a separable shoulder member 16' fitted within 115 a suitable depression 17 formed in the yoke and provided at its opposite ends with downwardly depending securing lugs 16^a adapted to prevent longitudinal displacement of the lug members 16 by engaging the outer faces 120 of the yoke proper.

In Fig. 5 I have shown a further simple modification or equivalent form of clamping shoulder consisting of a separable shoulder element 18 provided with a key projection 19 on its under surface registering with a key way slot 20 suitably formed in the yoke member 3 as indicated.

A valuable and advantageous feature of my improved construction as illustrated 130

- consists in the desirable arrangement where-
by the wedge members 6 and 10 are pro-
vided with the ledges 8 and 8' which under-
lie the respective ends of the yoke member.
5 As a result thereof upon loosely assembling
the parts the yoke will be properly sup-
ported in effective alignment with the rails
so that preparatory to tightening of the
clamp the yoke is properly positioned so
10 that the clamping is effected by merely driv-
ing in the wedge and it is not necessary to
otherwise support the yoke during the tight-
ening operation. It will be further noted
15 that a further advantage is that in the event
of either of the wedges becoming loosened
the yoke will be maintained in effective
clamping position and is supported from
dropping down at either end.
- Having described my invention I claim:—
- 20 1. A rail clamp comprising a clamp bar
or yoke member having inwardly directed
end portions and a shoulder formed thereon
upwardly projecting from its upper or rail
engaging surface intermediate of said end
25 portions, a wedge member formed with a
rail engaging portion and an inclined wedg-
ing surface adapted to be interposed between
one end of the yoke and a rail for clamping
the rail against said shoulder and means for
securing said wedge member in assembled
30 position, said shoulder being of substantially
the height of the rail base and non-project-
ing thereover, substantially as described.
2. A rail clamp comprising a clamp bar
or yoke member having inwardly directed
35 end portions and an integral shoulder
formed thereon upwardly projecting from
its upper or rail engaging surface interme-
diate of said end portions, said shoulder be-
ing arranged in engagement with one rail
40 only and of a height substantially equal to
the rail base, a wedge member formed with a
rail engaging portion and an inclined wedg-
ing surface adapted to be interposed between
one end of the yoke and a rail for clamping
45 the rail against said shoulder and means for
securing said wedge member in assembled
position and said wedge member being
formed at its lower edge with an outwardly
projecting ledge portion adapted to under-
50 lie the end portion of the yoke members, sub-
stantially as described.

In testimony whereof I have signed my
name to this specification.

EMIL CARL ZIMMERMAN.
